(57) **CLAIM**

The ornamental design for a tube for a breath analysis device, as shown and described.

DESCRIPTION

FIG. 1 is a perspective view of a tube for a breath analysis device according to a first embodiment of the claimed design.

FIG. 2 is a left side view of the tube for a breath analysis device of FIG. 1.

FIG. 3 is a bottom view of the tube for a breath analysis device of FIG. 1.

FIG. 4 is a right side view of the tube for a breath analysis device of FIG. 1.

FIG. 5 is an enlarged rear view of the tube for a breath analysis device of FIG. 1.

FIG. 6 is an enlarged front view of the tube for a breath analysis device of FIG. 1.

FIG. 7 is a perspective view of a tube for a breath analysis device according to a second embodiment of the claimed design.

FIG. 8 is a left side view of the tube for a breath analysis device of FIG. 7.

FIG. 9 is a bottom view of the tube for a breath analysis device of FIG. 7.

FIG. 10 is a right side view of the tube for a breath analysis device of FIG. 7.

FIG. 11 is an enlarged rear view of the tube for a breath analysis device of FIG. 7; and,

FIG. 12 is an enlarged front view of the tube for a breath analysis device of FIG. 7.
